United States Patent

Des. 235,900
Patented July 15, 1975

235,900

GOLF CLUB GRIP

Clifford A. Spencer, Akron, Ohio, assignor to
Eaton Corporation

Filed Jan. 4, 1974, Ser. No. 430,815

Term of patent 14 years

Int. Cl. D21—02

U.S. Cl. D34—5 GS

FIG. 4

FIG. 1

FIG. 2

FIG. 3

FIG. 5

FIG. 1 is a front elevational view of a golf club grip showing my new design;

FIG. 2 is a side elevational view taken from the left of FIG. 1 which is a mirror image of side elevational view taken from the right of FIG. 1;

FIG. 3 is a rear elevational view thereof;

FIG. 4 is a top view thereof; and

FIG. 5 is a bottom view thereof.

I claim:

The ornamental design for a golf club grip, substantially as shown and described.
